UNITED STATES PATENT OFFICE.

ALICE H. FLANDERS, OF CHICAGO, ILLINOIS, ASSIGNOR TO A. H. FLANDERS COMPANY, OF CHICAGO, ILLINOIS, A CORPORATION OF ILLINOIS.

DESIGN FOR A WOMAN'S BLOUSE.

54,837.

Specification for Design.

Patented Apr. 13, 1920.

Application filed December 10, 1919. Serial No. 343,934. Term of patent 3½ years.

To all whom it may concern:

Be it known that I, ALICE H. FLANDERS, a citizen of the United States, residing at Chicago, in the county of Cook and State of Illinois, have invented a new, original, and ornamental Design for a Woman's Blouse, (No. 187,) of which the following is a specification, reference being had to the accompanying drawing, forming part thereof.

The figure is a front elevation of a blouse showing my new design.

I claim:

The ornamental design for a woman's blouse, as shown.

ALICE H. FLANDERS.
